BUCKLE

William Woodward Dillon, New York, N. Y.

Application February 12, 1938, Serial No. 190,163

1 Claim. (Cl. 24—180)

This invention relates to a buckle and the combination of the same with strap ends that it is adapted to secure together.

The object of the invention resides in the provision of a buckle for securing strap ends together in such manner that their separation will be resisted by predetermined force and that their separation will be permitted upon the application of a force in excess of that predetermined force.

10 A further object of the invention resides in so constructing the buckle that it may be adjusted to resist the separation of the strap ends regardless of the application of force to the strap ends.

15 In the drawing I have illustrated an embodiment of my invention, but it is to be understood that I am not to be limited to the specific details therein illustrated but only insofar as is necessary to the claim.

20 In the drawing:

Figure 1 is a perspective view of the buckle showing the parts in the positions that they occupy when the strap ends are held positively against separation;

25 Figure 2 is a similar view showing the positions of the parts of the buckle when they are in the positions that they occupy when the strap ends are held against separation under the influence of a predetermined force;

30 Figure 3 is a perspective view of the buckle showing the interior of the same;

Figure 4 is a fragmentary perspective view illustrating the locking tongue mechanism; and

35 Figure 5 is a fragmentary sectional view showing the manner in which the positive detent is engaged with the sides of the body of the buckle.

40 Referring now specifically to the drawing, the buckle includes a housing 1 which has a longitudinal passage 2 therethrough, and which is open at one side as at 3.

45 The housing 1 is adapted to be secured to a strap end 4. The opposite strap 5 is adapted to pass through the longitudinal passage 2 of the housing so that the strap ends will lie in superimposed relation to each other.

50 In order that these strap ends may be secured together either positively or so that they will be released from each other upon the application of a predetermined force, I have provided the following mechanism: A tongue 6 is mounted upon a transverse rod 7 that is pivotally mounted within the housing 1 and between the sides thereof. The tongue 6 is adapted to engage through any 55 one of a series of openings 8 in one strap end

and is provided with a cam face 9. Normally the tongue 6 is urged in a direction opposite to that in which the free strap end 5 moves for disengagement from the opposite strap end 4 by a spring 10 that is anchored to the rod 5 and to the housing 1 at 11.

The tension of this spring 10 is such that it normally resists the movement of the tongue 6 in a direction which will permit the separation of the strap ends but when the effect of this predetermined tension is overcome by the application of a separating force to the strap ends, the tongue 6 will be moved against the tension of the spring until the opening 8 of the strap end 5, riding upon the cam surface 9, passes from 15 the tongue 6, thus releasing the strap end 5.

If it is desired to lock the tongue 6 against movement in the direction in which it will release the strap ends, the detent plate 12, which is pivoted at 13 within the housing 1 may be 20 swung into the position illustrated in Figure 1 where it will engage the tongue 6 and positively prevent its releasing movement.

On the other hand, this detent plate 12 may be swung into the position illustrated in Figure 2 25 where it will be out of the line of movement of the tongue 6 and will thus permit the tongue to move against the action of the spring 10 when sufficient force is applied to the strap ends 4 and 5. 30

To facilitate the operation of this detent plate 12, an opening 14 is provided which may be engaged by the finger of the operator and to insure the retention of the detent or locking plate 12 in its locking position as shown in Figure 1, I 35 have provided the plate with nibs 15 that are adapted to engage in recesses 16 in the side walls of the housing 1, this engagement being permitted by the flexing of the side walls and the engagement and disengagement being facilitated by the cam faces of the nibs 15 and the recesses 16.

40 Thus it will be seen that the strap ends may be secured together so that they will release automatically upon the application of a predetermined force or they may be locked together so that they will be held in this locked position regardless of the force that is applied to the strap ends and that tends to separate them.

45 It will be realized that this invention is applicable to many uses, as for instance, it may be incorporated in a dog collar. This incorporation in a dog collar, will, of course, make it possible to secure the collar ends together regardless of the force that is applied that tends to 50 55

separate them. On the other hand, the buckle may be adjusted so that upon the application of a predetermined force the strap ends will be released and the collar released from the dog.

5 While I have illustrated and described a particular construction embodying my invention I wish it understood that many variations of the details of this construction are possible.

I claim:

In a buckle, a housing, a tongue pivotally mounted in the housing, resilient means for resisting the movement of the tongue in one direction, and means for positively locking the tongue against movement in such direction, said latter means comprising a pivoted detent plate adapted to be swung into and out of its locking position. 5

WILLIAM WOODWARD DILLON.
